UNITED STATES PATENT OFFICE

2,493,630

SINGLE OR MULTIPLE KEY LOCK

Maurice Etienne Julliard, Paris, France

Application March 5, 1946, Serial No. 652,053
In France November 23, 1943Section 1, Public Law 690, August 8, 1946
Patent expires November 23, 1963

4 Claims. (Cl. 70—339)

1

Locks are known in which tumblers each provided with a web or projecting part are slidably in channels formed in a barrel rotatably mounted and extending on either side of a stationary ward provided with slots or cut-out portions in which said webs are engaged by springs when the lock is in closed position, said webs being provided with slots or recesses which may be brought, by means of keys provided with pins of different lengths, into coincidence with said ward so as to allow the barrel to rotate freely.

According to the present invention, a twofold safety can be attained by the combination of two combination devices similar to the one just defined, one of which controls the possibility of operation of the other.

The invention will be understood more easily by reference to the appended drawings in which two different embodiments of the invention are shown by way of example, viz:

Figure 1 is a perspective view of a single-combination 3-tumbler lock;

Figures 2 and 3 are two diagrammatical illustrations of the principle of the invention, as applied to a 2-tumbler lock, before and after unlocking respectively;

Figures 4 and 5 are two perspective views of a double-combination lock in the two successive steps of its operation;

Figure 6 shows the arrangement of the web-guiding channels and slots;

Figures 7 and 8 are two diagrammatical illustrations of the two successive steps of operation.

Figure 9 shows another modification in sectional view as shown in Fig. 1, the key *a* is formed in known manner with adjacent aligned pins *b*₁, *b*₂, *b*₃, . . . individually adjustable in their heights and which, when stuck into the bores *c*₁, *c*₂, *c*₃, . . . in the pair of barrels *d*₁, *d*₂, will act upon plungers or tumblers *e*₁, *e*₂, *e*₃, . . . slidably received in said bores and urged by their respective return springs *f*₁, *f*₂, *f*₃.

Secured between the barrels *d*₁, *d*₂ is a ward plate *h* which extends sidewardly to socket *h'* for carrying the barrel *d*₁ and which has a central aperture *m* through which extend connecting screws (not shown in Fig. 1) by which the barrels *d*₁ and *d*₂ are made rigid with each other.

The plungers *e*₁, *e*₂, *e*₃ carry respectively webs *g*₁, *g*₂, *g*₃ which are slidably received in channels *j*₁, *j*₂, *j*₃ in barrels *d*₁, *d*₂ and which project through corresponding slots *k*₁, *k*₂, *k*₃ cut in ward *h*.

It follows that normally the webs will act as latches, i. e. will prevent the barrels *d*₁ and *d*₂ (7 and 8 respectively). The channels *j*₁, *j*₂, *j*₃, *j*₄

2

from being rotated by means of a key by reason of the ward *h* being stationary.

However, the webs have notches, such as *l*₁, cut therein, and it will readily be understood that by suitably adjusting the heights of pins *b*₁, *b*₂, *b*₃ it is possible to bring the notches *l*₁, . . . into alignment in the plane of ward *h*. At that moment the webs *g*₁, *g*₂, *g*₃ no longer exert their latching action, which means that, by acting upon the key *a* it is possible to rotate both barrels *d*₁ and *d*₂, whereby the lock bolt can be operated, e. g. by means of a finger *r* co-operating with a rack *s*.

The notches *l*₁, . . . are cut in the webs at various points of their lengths, this allowing of an unlimited number of combinations, and the individual pins *b*₁, *b*₂, *b*₃ are adjusted correspondingly in their lengths simultaneously to bring the slots *l*₁, . . . into register in one and the same plane.

20 Each web could have several slots cut therein. For instance, each web on the key of a hotel bedroom door-lock is formed with two slots, it will be possible to open the lock on the basis of two different combination with the aid of two different keys, one in the hands of the traveller and the other possessed by the waiter.

Also the number of the plungers and the direction of the channels *j*₁, *j*₂, *j*₃ cut for the passage of the webs can be varied unlimitedly.

25 The pushing action on tumblers *e*₁, *e*₂ to bring slots *l*₁, *l*₂ in webs *g*₁, *g*₂ into alignment is quite clearly shown in Figs. 2 and 3 which have been simplified to the utmost with the illustration of the only two tumblers.

30 In embodiments where an increased safety is required it is possible to combine several similar combination devices designed to lock one another.

For instance, it is possible, as in the embodiment 40 shown by way of Example in Figs. 4 to 8, to provide two series of plungers or tumblers, *e*₁, *e*₂, *e*₃, and *e*₄ and *e*₁', *e*₂', *e*₃', *e*₄' respectively, arranged crosswise to each other.

45 The lock then comprises three barrels *d*₁, *d*₂, *d*₃ separated by two wards *h*₁, *h*₂, the former being stationary and receiving the foremost barrel *d*₁ in its extension *h*₁' while the latter *h*₂ acts as the socket for the intermediate barrel *d*₂.

The barrels *d*₁, *d*₂, *d*₃ rigidly interconnected by 50 screws or studs *n* have longitudinal holes bored therein to slidably receive the tumblers, and channels *j*₁, *j*₂, *j*₃, *j*₄, . . . are provided in said barrels as guideways for the webs on the respective tumblers *g*₁, *g*₂, *g*₃', *g*₄' alone being visible in Figs. 7 and 8 respectively). The channels *j*₁, *j*₂, *j*₃, *j*₄

may extend relatively to one another as shown in Fig. 6, their outer ends being directed radially.

One series of tumblers $e_1 \dots e_4$ cooperates with the one ward h_1 and the other series $e'_1 \dots e'_4$ with the other ward h_2 .

The first socket h'_1 is stationary and is formed with a slot p extending over 90° and adapted to limit the amplitude of rotation of the other socket h'_2 during the first stage of the unlocking process, said last-mentioned socket being provided with a stroke-limiting lug q .

Finally, the last barrel d_3 carries a tenon r designed to actuate the lock bolt or bolts. The operation of such a lock will now be understood easily.

At the beginning of the first step, the pins on the so-called "first combination" key are stuck into the bores in which the first series (then vertically aligned) of tumblers e_1, e_2, e_3, e_4 (Figs. 4 and 7) are housed; the slots in the webs $g_1, \dots, g_4$ of the tumblers are thus brought into the plane of the ward h_1 , which makes it possible to rotate the barrels d_1, d_2, d_3 and also the movable ward h_2 , then held latched between d_2 and d_3 by the webs on the plungers or tumblers belonging to the second series, by an angle of 90° , the amplitude of the rotation of d_1, d_2, d_3, h_2, h'_2 being limited by the engagement of abutment means in the form of the lug q within the slot p .

As the second step, the pins on the so-called "second combination" key are stuck into the bores containing the second series (then brought in turn to vertical alignment) of tumblers e'_1, e'_2, e'_3, e'_4 (Figs. 5 and 8); the slots in the webs $g'_1 \dots g'_4$ thereon are thus brought into the same plane, that of the ward h_2 , which allows further to rotate the barrels d_1, d_2, d_3 and the tenon r which only then begins to actuate the lock bolt or bolts.

It will be appreciated that a considerable number of "combinations" can thus be arrived at. Besides, the two keys can be combined into one single key provided with pins adjustable in their heights between the first and the second steps.

The latching action could also be performed (Fig. 9) by the plunger $e_1 \dots e_4$ itself instead of actually projecting web-like portion of the same, provided it were given a sufficiently large diameter, in which case grooves $l_1 \dots l_4$ instead of slots would be cut directly in the plunger shaft and the outline of the aperture m in the several wards h should be altered accordingly.

Moreover, the invention lends itself to all sorts of modifications in the shapes and the constructional details, particularly depending on the lock type, the number of "combinations," the degree of safety aimed at and the application contemplated.

Having thus described the invention, what is claimed as new and desired to be secured by Letters Patent, is:

1. In a combination lock in which the bolt thereof is operable by means of two keys, each of which has a plurality of pins of different lengths; a lock body rotatably mounted and provided with three coaxial barrels which are spaced from each other but rigidly connected together, said barrels

being provided with two sets of longitudinal guide channels aligned to extend through said three barrels, respectively, said two sets of channels being adapted to receive said pins of said two keys, successively, means carried by said body and adapted to actuate the lock bolt, a first ward fixedly located between the first and the second of said barrels and provided with cut-out portions, a second ward rotatably mounted between the second and the third of said barrels and provided with cut-out portions, abutment means connected to said lock body and adapted to limit the amplitude of rotation of said second ward, a tumbler accommodated in each channel and movable therein and provided with projecting portions, said projecting portions being adapted to engage said cut-out portions in the first ward for one set of channels and in the second ward for the other set of channels, at least one recessed portion in each of said tumblers remaining out of engagement with said wards when the respective tumbler is moved in its channel, spring means in said channels urging said tumblers to a position in which a projecting portion of said tumblers is engaged in a cut-out portion of the corresponding cooperating ward and adapted to yield and to allow said recessed portion in each of the tumblers to coincide with the corresponding ward when the pins of the corresponding key are introduced into the corresponding set of channels, whereby the first key when introduced into the first set of channels will cause rotation of said three barrels and of the second ward by an angle corresponding to the limited amplitude of rotation of said second ward, and the second key when introduced into said second set of channels will cause said three barrels to rotate independently of said wards, whereby said lock bolt is actuated.

2. In a combination lock according to claim 1, wherein said second ward is rotatably mounted on said first ward.

3. In a combination lock according to claim 1, wherein said two sets of channels are disposed at right angles to each other, said means adapted to limit the amplitude of rotation of the second ward allowing displacement of said second ward within an angle of 90° relatively to said first ward.

4. In a combination lock according to claim 1, wherein said first ward is provided with a circular flange for housing and centering said first barrel, said second ward being provided with a circular flange for centering the second barrel.

MAURICE ETIENNE JULLIARD.
